UNITED STATES PATENT OFFICE.

HOWARD C. TAYLOR, OF SALT LAKE CITY, UTAH.

GASOLINE-TANK APPLIANCE.

Application filed March 31, 1923. Serial No. 629,043.

To all whom it may concern:

Be it known that I, HOWARD C. TAYLOR, a citizen of the United States, residing at Salt Lake City, in the county of Salt Lake and 5 State of Utah, have invented certain new and useful Improvements in a Gasoline-Tank Appliance, of which the following is a specification.

This invention relates to tanks of liquid 10 storage receptacles and comprehends vital improvements in the filling caps therefor.

One of the prime objects of the invention is to provide a novel attachment for the filling caps of gasoline tanks of automobiles for 15 effectively preventing the stealing of the gasoline from the tank through the filling opening, by the use of a siphon or the like.

Another prime object of the invention is to provide a novel guard for association 20 with the ordinary filling neck of a gasoline tank for effectively preventing the inserting of a hose or other siphoning tube in the tank, the guard being so constructed as to permit the ordinary cap of the filling neck to be 25 associated with said attachment.

A further prime object of the invention is to provide an improved attachment for the filling openings of gasoline tanks embodying a collar for receiving the ordinary neck 30 of the gasoline opening and the closing cap therefor, and a novel guard cast or otherwise connected with the collar for preventing the inserting of a hose into said tank.

A still further object of the invention is 35 to provide a novel attachment for gasoline tanks of automobiles of the above character, which will be durable and efficient in use, one that will be simple and easy to manufacture and one which can be placed upon 40 the market and incorporated with any type of gasoline tank at a minimum cost.

With these and other objects in view, the invention consists in the novel construction, arrangement and formation of parts, as will 45 be hereinafter more specifically described, claimed and illustrated in the accompanying drawings, in which drawings:

Figure 1 is a plan view of the improved attachment.

Figure 2 is a vertical central section 50 through the attachment, showing the same incorporated with a gasoline tank.

Figure 3 is a view similar to Figure 2 showing a modified form of the attachment.

Figure 4 is a vertical diametric section 55

through the form of the attachment shown in Figure 3 of the drawings.

Figure 5 is a fragmentary vertical section showing another form of the attachment incorporated with a gasoline tank. 60

Referring to the drawings in detail, where in similar reference characters designate corresponding parts throughout the several views the letter A generally indicates the improved attachment and B a gasoline tank, 65 with which the same is associated. The tank B is of any preferred construction and is provided with the ordinary filling opening 10, which is surrounded by the upstanding sleeve 11. The sleeve 11 in this type of tank 70 is provided external male threads 12. The threads 12 are generally provided for the reception of the closing cap 13 which can be of the usual construction, and this cap as shown consists of the internally threaded body 14 75 and the polygonal extension 15 for permitting the turning of the cap by a wrench or some similar tool.

As clearly shown in Figure 2 of the drawings the improved attachment A is disclosed 80 between the neck 11 and the cap 13 and this attachment embodies upper and lower collars 16 and 17. The lower collar 17 is of a relative larger diameter than the upper collar 16 and is provided with internal female 85 threads for the reception of the threads 12 formed on the sleeve 11. After the collar 17 is threaded on the sleeve 11 the same can be secured in place against movement of unauthorized persons by a suitable pin or the 90 like 18. It is preferred to have the outer surface of the collar 17 of a polygonal configuration as indicated by the reference character 19' to permit the ready engagement thereof by a nut wrench. In view of 95 the fact that the upper collar 16 is of a smaller diameter than the lower collar 17, the same are offset in relation to each other, which forms an internal shoulder 19, that is adapted to fit snugly on the upper surface 100 of the sleeve 11 when the collar 17 is in position. The inner surface of this collar 16 is then disposed flush with the inner surface of the collar 17. An outer annular shoulder 20 is also formed and the outer surface of the collar 16 is provided with external male threads for reception of the internally threaded body 14 of the cap 13. If so desired, a gasket 21 can be placed upon the 105 upper surface of the collar 16 in engagement

110

with the cap 13 so as to prevent the leakage of the fluid contained in the tank between the collar and the said tank.

The upper collar 16 of the attachment A 5 carries the inwardly extending guard 25 which in this instance, is cast integral with the said collar and embodies a plurality of depending equi-distantly spaced arms 26 which are arranged in spaced relation to 10 the collar 17 so as to permit the threading of the collar upon the sleeve 11. The extreme lower ends of these arms 26 terminate in inwardly extending fingers 27 which extend toward a common point. These arms 15 26 and inwardly extending fingers 27 can be joined by cross ribs 28 which act as means for preventing the inserting of a hose through the said arms and fingers. If preferred, the ribs 28 can support short bars 29 20 which act as further means for preventing the insertion of a hose or tube in the tank.

It is obvious that when the improved attachment is connected with the sleeve 11 that the inserting of a hose or tube in the tank B 25 is absolutely precluded and, thus the stealing of gasoline by the siphoning of the same from a tank is eliminated.

While the guard 25 also forms a body for permitting the holding of chamois or the like so that the gasoline can be strained when pouring the same in the tank, I prefer to surround the guard by a suitable wire screen 30 of a relatively fine mesh. This of course will prevent the entrance of any foreign 35 substance into the tank with the gasoline and also act as a fire preventive.

In Figures 3 and 4 I have shown a modified form C of the improved attachment and it can be seen at the start that this form is 40 identical with the form A shown in Figures 1 and 2, with the exception of the guard. In this instance I provide a sheet metal guard 40 which includes a cylindrical body 41 having a lower frusto-conical extension 42. The lower end of the body 41 and the frusto-conical extension 42, are provided with a plurality of perforations 43 so as to 45 permit the free flow of gasoline through the guard into the tank. The extreme upper edge of the body 41 is provided with an offset annular attaching flange 44 which is riveted or otherwise secured as at 45 to the upper collar 16. The provision of the offset 50 attaching flange 44 places the body 41 from the lower collar 17 so as to permit the convenient attachment thereof to the sleeve 11 as heretofore stated.

In Figure 5 I have shown a still further modified form D of the improved attachment and this form D is particularly adapted to be associated with tanks having collars 50 which are provided with internal female threads 51 for the reception of caps 52 of the plug type. As shown the cap 52 55 embodies an annular externally threaded

body 53. The attachment D includes upper and lower collars 55 and 56 and in this instance the upper collar 55 is of a greater diameter than the lower collar 56 which is provided with external male threads for 70 fitting within the sleeve 50. The upper collar 55 is of course provided with internal female threads for the reception of the externally threaded body 53 of the plug cap 52. It is to be noted also in this form that the guard 75 designated by the reference character 57 is attached to the lower collar 56 and this guard can be of the type shown in Figures 1 and 2 or the type shown in Figures 3 and 4, and functions in the same manner. 80

From the foregoing description, it can be seen that I have provided an improved attachment for gasoline tanks of automobiles, which will effectively prevent the stealing of gasoline therefrom or the siphoning of 85 the gasoline from out of the tank.

Changes in details may be made without departing from the spirit or the scope of this invention.

What I claim as new is:— 90

1. The combination with a storage tank embodying a filling opening, of a heavy rigid guard member associated with said filling opening for permitting of the filling of the tank through said opening and the 95 preventing of the insertion of a tube or the like through said opening.

2. The combination with a tank having a filling opening therein, a filling neck surrounding said opening, of an attachment 100 for preventing the inserting of a siphon hose through said opening embodying a heavy rigid metal guard, and means for connecting the guard with the said neck.

3. The combination with a tank having a 105 filling opening therein, and a neck surrounding said opening, of an attachment for the tank embodying a heavy fabricated cast metal guard for preventing the inserting of a hose through said opening and an 110 attaching collar carrying said guard for engaging the neck.

4. The combination with a tank having a filling opening therein and a neck surrounding said opening, of a cap for said neck, of 115 an attachment interposed between the neck and cap for preventing the inserting of a hose through said neck embodying a lower collar for engaging the neck, an upper collar for receiving the cap, and a fabricated 120 guard carried by one of said collars and extending into the tank.

5. The combination with a tank having a filling opening therein, a neck surrounding the opening and a cap for said neck, of 125 an attachment for the tank for preventing the inserting of a siphoning hose through said neck embodying upper and lower collars for receiving the neck and cap respectively, a guard connected with one of said 130

collars having openings therein for permitting the flow of a liquid therethrough, a screen surrounding said guard.

6. As a new article of manufacture, an attachment for gasoline filling tanks for preventing the siphoning of the gasoline through the filling opening comprising a pair of offset externally and internally threaded collars and a heavy fabricated cast metal guard connected with one of said col-

7. As a new article of manufacture, a device for preventing the siphoning of gaso-

line from a gasoline tank through the filling opening thereof comprising a pair of offset 15 integrally connected collars provided with internal and external threads respectively, and a guard connected with one of said collars embodying a cylindrical body portion and a frusto-conical lower portion.

In testimony whereof I affix my signature in presence of two witnesses.

HOWARD C. TAYLOR.
